UNITED STATES PATENT OFFICE

WILLIAM HOPPER, OF OLD KILPATRICK, SCOTLAND, ASSIGNOR TO THE SINGER MANUFACTURING COMPANY, OF ELIZABETH, NEW JERSEY, A CORPORATION OF NEW JERSEY

DESIGN FOR A SEWING MACHINE FRAME

Application filed September 12, 1931, Serial No. 41,072, and in Great Britain August 26, 1931. Term of patent 14 years.

To all whom it may concern:

Be it known that I, WILLIAM HOPPER, a subject of the King of Great Britain, residing at Dalnotter Hill, Old Kilpatrick, Dumbartonshire, Scotland, have invented a new, original, and ornamental Design for Sewing Machine Frames, of which the following is a specification, reference being had to the accompanying drawings, forming part thereof.

Fig. 1 is a perspective view of the front side of a sewing machine frame. Fig. 2 is a fragmentary view of the opposite side of the bracket arm showing my new design.

I claim:

The ornamental design for a sewing machine frame, as shown and described.

WILLIAM HOPPER.
